F. H. BROWN

BURNER

Filed April 26, 1920

UNITED STATES PATENT OFFICE.

FRANCIS H. BROWN, OF GLENOLDEN, PENNSYLVANIA, ASSIGNOR TO PETROLEUM
HEAT AND POWER COMPANY, OF BOSTON, MASSACHUSETTS, A CORPORATION
OF DELAWARE.

BURNER.

Application filed April 26, 1920. Serial No. 376,747.

To all whom it may concern:

Be it known that I, FRANCIS H. BROWN, a citizen of the United States, residing at Glenolden, in the county of Delaware and State of Pennsylvania, have invented an Improvement in Burners, of which the following description, in connection with the accompanying drawings, is a specification, like characters on the drawings representing like parts.

The invention to be hereinafter described relates to burners, and more particularly to burners employing oil as a fuel.

In my copending application Serial No. 374,396 filed April 16, 1920, is shown, described and claimed a fuel oil burner provided with means for introducing the oil and steam or other atomizing agent into the burner and having provision for efficient atomization of the oil so as to break the same up into substantially a gaseous state. Said burner is also provided with an arrangement of passages or nozzles having provision for producing a secondary atomization effect, the construction being such that if the oil in its transit through the burner after the first atomization should return from a gaseous to a more or less liquid state, the means for producing the secondary atomization will efficiently atomize the oil and prevent projecting of globules or liquid particles of oil into the furnace.

In the embodiment of the invention selected for illustration in said application, the secondary atomizing means is located at the tip or delivery end of the burner, so that the atomized oil issues directly therefrom into the furnace.

In some instances it may be desirable to provide a burner with secondary atomization means which will have the advantages of the secondary atomization means disclosed in said application, but located within the burner. In the present instance of the invention, this secondary atomizing means is located closely adjacent to the tip or delivery end of the burner, but the position thereof with respect to the tip or delivery end may be varied provided that the atomized oil on issuing from the secondary atomizing means does not travel a sufficient distance in the burner to allow return there-

of from a gaseous to a more or less liquid state.

The delivery end of the burner projects into the furnace and is subjected to the high temperature thereof, which may tend to cause the oil to carbonize on parts of the means for producing the secondary atomization, and therefore, it may be desirable to provide a delivery end or tip for the burner which will tend to protect the secondary atomizing device from such carbonization effect.

Also, for different conditions it may be desirable to employ delivery ends or tips for the burner of varying character. For example, in some instances it is desirable to provide a tip which shall have a single delivery orifice, and in other instances it may be desirable to provide a tip which shall have a plurality of orifices, and it may be desired to vary the shape of the orifice or orifices. Another purpose of the invention, therefore, is to provide a delivery end or tip for the burner which may be located beyond the secondary atomizing device, and may be detachably secured to the burner so as to admit ready removal thereof and substitution of others therefor.

There are further advantages in such a delivery end or tip, since it may serve to produce a still further atomization of the oil after delivery thereof from the secondary atomizing means.

With the aforesaid and other purposes in view, the character of the invention will be understood by reference to the following description of one good form thereof shown in the accompanying drawing, wherein:

Fig. 1 is a vertical longitudinal section through a burner embodying the invention;

Fig. 2 on an enlarged scale is a vertical transverse section taken on line 2-2 of Fig. 1; and

Fig. 3 on an enlarged scale is a front end view of the burner.

Referring to the drawing, the burner shown therein as one good form of the invention comprises a body or gun 1 conveniently of tubular form and of substantial length.

Any suitable means may be provided for introducing the oil and steam or other atom-

izing agent into said gun. In the present instance of the invention, this means comprises a charging device 3 provided with passages for the oil and steam or other 5 atomizing agent, said passages being conveniently in the form of a central steam conducting passage 5 and an annular oil conducting passage 7 respectively receiving steam and oil from pipes 9 and 11 provided 10 with suitable valves 13 and 15. These passages may have delivery nozzles 17 and 19 relatively adjustable and contracted so as to increase the velocity of the streams of steam and oil issuing therefrom. The construction 15 is such that the oil may be delivered in an annular stream transversely to the central stream of oil, so that the steam will impinge against the annular stream of oil focused and directed transversely thereof, thereby efficiently to atomize or break up 20 the oil.

This charging device may be substantially the same as that disclosed in my copending application Serial No. 367,629, filed March 25 22, 1920, and also disclosed in the application 25 first referred to herein.

The mixture of atomized oil and steam issuing from the charging device will pass 30 through the gun 1 toward the delivery end thereof. As stated, one of the purposes of the invention is to provide means within the burner for efficiently producing secondary atomization of the oil so as to break up and 35 thoroughly atomize any globules or particles of oil which may have formed in the course of the transit of the mixture through the burner. This secondary atomizing means, in the present instance of the invention, comprises a neck 21 having a flange 23 at the 40 rear end thereof threaded to the front end of the gun 1. Adjustably connected to said neck conveniently by threaded attachment is a nozzle 25 contracted to present a delivery mouth 27.

Mounted within the neck 21 is a neck 29 conveniently connected thereto by a web 31 having a plurality of openings or ports 33 therein for allowing the oil and steam mixture to pass from the gun into the annular 50 passage 35 between the necks 21 and 29. Adjustably connected to the neck 29 conveniently by threaded attachment is a nozzle 37 contracted to present a delivery mouth 39 adjacent the delivery mouth 27 of the outer nozzle.

The construction is such that the oil and steam mixture may pass from the gun both 60 into the annular passage 35 and the central passage 41. The construction and shape of the contracted nozzles 25 and 37 is such that the annular stream passing through the passage 35 is concentrated against and caused to project transversely with respect to the stream issuing from the central passage 41, and the velocity of said streams is materially

increased. As a result, a secondary atomization of the oil is produced which breaks up the globules or particles of oil into a substantially gaseous state.

This secondary atomizing means may be 70 suitably located within the burner, and the distance therefrom from the delivery end of the burner may be varied, but preferably the secondary atomizing means is located closely adjacent to the tip or delivery end of the 75 burner.

As stated, one of the purposes of the invention is to provide a delivery end or tip for the burner located beyond the secondary atomizing means. In the present instance, 80 this delivery end or tip is formed of thin sheet metal 43 preferably curved and provided with a flange or margin 45 confined between the end of the outer nozzle 25 and a flange of a collar 47 which may be threaded to the outer nozzle 25. This tip may be provided with an appropriate orifice, in the present instance, in the form of an elongated slit 49.

The construction is such that the oil and steam mixture issuing from the secondary atomizing means will impinge against and be deflected by the inner curved surface of the tip to the slit orifice 49, and thereby cause 95 further atomization of the oil, so that on delivery of the mixture from the burner, the oil will be in a desirable gaseous state for efficient combustion effect. When it is desired to substitute a new or different tip for the tip 43, it is merely necessary to unscrew 100 the collar 47 to liberate the tip 43 and then place the new tip in the collar and screw the latter back onto the outer nozzle 25 so as to confine its flange between the collar and the nozzle.

To facilitate application of the neck 21 to the gun, the flange 23 may have slabbed off faces 23^a adapted to receive a wrench. To facilitate relative adjustment of the outer and inner nozzles 25 and 37, they may be 110 respectively provided with a series of ribs 25^a and 37^a extending longitudinally thereof. To facilitate application to and removal of the collar 47 from the nozzle 25, said collar may have a series of ribs 47^a extending longitudinally thereof. In assembling the parts, the neck 21 may be screwed onto the gun, then the inner nozzle 37 may be screwed onto the inner neck 29, and then the outer nozzle 25 may be screwed onto the neck 21. The tip 43 may be applied to the outer nozzle as described.

It will be noted that in the operation of the burner described, the parts of the atomizing devices are fixed, and that there are no valves or movable parts which are liable to get out of order. As a result, the construction is such that it can be relied upon continuously to produce uniform atomization 125 and efficient delivery of the oil.

It will be understood that the invention is not limited to the specific embodiment shown, and that various deviations may be made therefrom without departing from the spirit and scope of the appended claims.

What is claimed is:—

1. A burner comprising, in combination, a body having a delivery tip provided with an orifice, means for conducting the oil and atomizing fluid to the body and for atomizing the oil as it is delivered to the body, and a secondary atomizing means located within the body between the first atomizing means and said tip and comprising a pair of adjustable nozzles one within the other.

2. A burner, comprising, in combination, a body having a delivery tip provided with an orifice, means for atomizing oil, an orifice, and means located in the burner adjacent said tip for producing secondary atomization of the oil, and comprising passages for conducting streams of atomized oil with provision for concentrating one stream of atomized oil against the other to promote further atomization of the oil prior to its discharge from said tip.

3. A burner, comprising, in combination, means for introducing oil and atomizing

fluid into the burner with provision for atomizing the oil, means located within the burner for producing secondary atomizing of the oil and comprising outer and inner nozzles each constructed and arranged to receive the atomized oil and to discharge it in the form of impinging streams to increase atomization of the oil, and a removable orifice tip for delivering from the burner the mixture delivered from the secondary atomizing means.

4. A burner, comprising, in combination, a body, a charging device for introducing oil and atomizing fluid into the burner with provision for atomizing the oil, a secondary atomizing means located within the burner remotely from said charging device and comprising a pair of nozzles, one within the other, and having closely adjacent mouths for concentrating streams issuing from said nozzles against one another to promote atomization of the oil, and a thin metal orifice tip for delivering from the burner the atomized mixture issuing from the secondary charging means.

In testimony whereof, I have signed my name to this specification.

FRANCIS H. BROWN.
